SEWING MACHINE

Hans Hacklander, Linden, N. J., assignor to The Singer Manufacturing Company, Elizabeth, N. J., a corporation of New Jersey

Application September 22, 1939, Serial No. 296,031

29 Claims. (Cl. 112—16)

This invention relates to sewing machines of the type wherein the material being stitched is adapted to be supported and fed through the machine by feeding wheels or "cups."

The present improvement is a modification of the machine disclosed in my pending application Serial No. 293,155, filed Sept. 2, 1939, and has for its primary object the provision of a simplified stitch-forming mechanism which is durable in operation, comparatively inexpensive to manufacture, and easy to assemble and repair.

A further object of the invention is the provision of an improved looper-drive by means of which the looper is given a short throw or movement in proper timed relation with the needle.

Another object of the invention is to provide an improved stitch-finger about which the over-edge stitches are formed and set, which stitch-finger is shaped so as to aid in setting a uniformly tight stitch with a minimum distortion of the fabric.

With the above and other objects in view, as will hereinafter appear, the invention comprises the devices, combinations, and arrangements of parts hereinafter set forth and illustrated in the accompanying drawings of a preferred embodiment of the invention from which the several features of the invention and the advantages attained thereby will be readily understood by those skilled in the art.

In the accompanying drawings, Fig. 1 is a right side elevation of a sewing machine embodying the invention with a portion of the frame-wall broken away to expose actuating mechanism within the frame.

Fig. 2 is an enlarged perspective view of the baffle-member for preventing the escape of oil from within the machine-standard.

Fig. 3 is a horizontal sectional view taken through the machine-frame, illustrating the drive for the looper and the spreader.

Fig. 4 is an enlarged top plan of the improved stitch-finger.

Fig. 5 is a front elevation of the elements shown in Fig. 4.

Fig. 6 is a right side elevation of the elements shown in Fig. 4.

Fig. 7 is a front elevation of the upper portion of the machine with the outer feed-cup removed to show the arrangement of the supporting rock-shafts for the looper and the spreader.

Fig. 8 is a view similar to Fig. 7, but illustrating the machine fitted with a threaded looper instead of a non-threader spreader, adapting the machine to produce a three-thread seam.

Fig. 9 is a front elevation of the upper portion of the machine-frame, showing the uncurling device in its operative position (full lines) and in its inoperative position (dotted lines).

Fig. 10 is a disassembled perspective view showing the various elements of the uncurling guide latching device and the means for releasing the same.

Fig. 11 is a front elevation of the uncurling guide latching device with the control-arms partially broken away to show the relative positions of the latches when the guide is in operative position.

Fig. 12 is a view similar to Fig. 11, showing the relative positions of the latches when the guide is in inoperative position.

Fig. 13 is an enlarged fragmentary perspective view of the stitch-finger, needle and looper, illustrating the way in which the needle-thread-loop positioning fin controls the needle-thread-loop so that it may be entered by the point of the looper.

Fig. 14 is an enlarged fragmentary perspective view of the stitch-finger and stitch-forming devices, showing how the spreader lays one limb of the looper-thread-loop over the crest of the looper-thread-loop position shoulder of the stitch-finger.

Fig. 15 is a top plan view of the elements as shown in Fig. 14.

Fig. 16 is an enlarged fragmentary perspective view similar to Fig. 14, but showing the spreader at the end of its loop-distending stroke and one limb of the looper-thread-loop in the trough at the base of the looper-thread-loop position shoulder of the stitch-finger.

Fig. 17 is a top plan view of the elements as shown in Fig. 16.

Referring in detail to the drawings, the machine in which one embodiment of the invention is incorporated is constructed in accordance with the disclosure in my above mentioned pending application, and differs therefrom only in such particulars as hereinafter described. The machine illustrated includes a machine-frame having a standard 2 and a laterally projecting overhanging bracket 3. Supported by the standard 2 is an inner feed-cup 4 which cooperates with an outer feed-cup 5 depending from the laterally projecting overhanging bracket 3. As is common in machines of this type, the two feed-cups 4 and 5 support and feed the fabric sections past the stitch-forming devices at a uniform rate.

The standard 2 of the machine-frame is

formed adjacent its top with a horizontal partition 6 which divides the machine-frame into a splash-lubrication compartment 7 and a belt-compartment (not shown) in the overhanging bracket. As clearly illustrated in my pending application previously referred to, the splash-lubrication compartment 7 is closed at the bottom by means of a removable plate (not shown).

Disposed in the splash-lubrication compartment 7 transversely of the machine-frame is a main-shaft 8 journaled at its opposite ends in bushings 9 and 10, Fig. 3, each of which is fixedly secured in a boss 11 provided in the standard wall preferably by screws 12 extending through a flange 13 formed on the outer end of each of the bushings. Mounted on the opposite ends of the main-shaft 8 are the usual balance-wheels 14, each having preferably a V-shaped belt-groove 15. The shaft-bearing in each bushing is lubricated by oil splashed throughout the compartment 7 by the connections actuated by the main-shaft 8. To prevent leakage of oil, the main-shaft at its opposite ends is provided with spiral grooves 16 which during the operation of the machine feed the excess oil in the shaft bearing back into the lubrication compartment 7. In addition to this oil-guard, each bushing is formed at its outer end with an internal oil-collecting circular recess 17 entered by a reduced hub-portion 18 of the balance-wheel 14. Formed in the reduced hub-portion 18 are several circular oil-collecting grooves 19. In the event that some oil should leak onto the hub of the balance-wheel 14 this oil is collected in the grooves 19 and is thrown off by centrifugal force into the internal recess 17 and is returned into the splash-lubrication compartment 7 by a return port (not shown) formed in the lower portion of the bushing.

Bushing 10, as shown in Fig. 3, is preferably formed with an extended inner end-portion 20 which provides a relatively long bearing for the main-shaft 8 rigidly supporting the same and preventing it from whipping or vibrating excessively during the high speed operation of the machine.

Referring now to the stitch-forming devices, the needle 21 is fixed in a needle-clamp 22 secured upon a horizontally disposed reciprocating hollow needle-bar 23 journaled at its outer end in a bushing 24 fixed in the wall of the machine-frame 1 and at its inner end in a bushing 25 secured by a screw 26 in an aperture 27 provided in an internal boss 28 formed on the machine-frame 1. To facilitate assembly, the aperture 27 in the boss 28 opens into the outer surface of the machine-frame and is normally closed by a screw-plug 29.

The needle-bar intermediate its end has clamped thereon preferably by means of a screw 30, Fig. 3, a collar 31 provided with an upstanding guide-lug 32 adapted to slide in a guideway between gibs 33 secured to the bottom of the horizontal partition 6 by screws 34. The function of the guide-lug 32 is to provide means for preventing the needle-bar 23 from turning in its bearings as the same is reciprocated. Depending from the collar 31 is a lug 35 connected by a link 36 to the upper arm of a rock-lever 37 having an elongated hub 38, see Fig. 3, journaled between collars 39 upon a fulcrum rod 40 fixed in spaced lugs 41 formed upon the machine-frame 1. Connected to the lower arm of the rock-lever 37 is a pitman 42 which is connected at its other end to a crank 43 formed in the main-shaft 8.

From the above, it will be obvious that rotation of the main-shaft 8 imparts to the needle-bar 23, through the connections just described, an endwise reciprocatory motion in time with the other stitch-forming devices now to be described.

Cooperating with the needle 21 is a looper 44, of the threaded type, which is constructed and actuated so that it seizes the thread-loop cast out by the needle 21 during the beginning of the needle-return or withdrawal stroke, thereby to enchain the needle-thread-loop with the thread T_p passing through the eye of the looper 44. The looper 44 is formed with a flattened shank 45 secured by a screw 46 in a recess provided in a looper-carrier 47 fastened by set-screws 48 upon the outer end of a comparatively short supporting shaft 49 journaled, in an angular relation to the needle-bar 23, in the lower portion of a bracket 50 depending from beneath the laterally projecting overhanging bracket 3 of the machine-frame 1. Fastened upon the inner end of the looper supporting shaft 49 by set-screws 51 is a downwardly extending rock-arm 52, the lower end of which is connected through a ball-and-socket joint with one end of a link 53 connected at its other end through a ball-and-socket joint to a lateral extension 54 secured by the screw 55 to the outer end of the needle-bar 23. To steady the link 53 and prevent the same from turning about its longitudinal axis, the link has fixed upon the top thereof a forked member 56 which straddles a pin 57 extending upwardly from the ball on the free end of the lateral extension 54.

The function of the looper 44, as indicated briefly above, is, firstly, to seize the thread-loop cast out by the needle 21, thereby enchaining the same with the thread carried by the looper, and secondly, to position that portion of thread carried by the looper and adjacent the looper-eye so that the looper-thread can be engaged by a spreader which presents the looper-thread-loop to the needle for entrance by the latter. In the machine disclosed these two steps are effectively carried out by a simple oscillation of the looper 44 about the longitudinal axis of the supporting shaft 49. In the machine disclosed, an oscillatory movement of the looper 44 is the only motion required to effect concatenation of the needle-thread-loop with the looper-thread and have the looper present a thread-loop to the spreader, because of the angular arrangement of the looper supporting shaft 49 with respect to the longitudinal axis of the needle-bar 23. It will be understood that the looper point travels in a single plane which is preferably at an acute angle with a vertical plane passing through the longitudinal axis of the needle-bar.

As is general in sewing machines, the needle during the initial portion of its withdrawal stroke forms or casts out a thread-loop which is subsequently seized and entered by the point of the looper so that it may be enchain with the looper-thread. To insure invariable seizure of the needle-thread-loop by the looper it is desirable that the looper dwell or have no appreciable movement when in its retracted position and during the initial portion of the needle withdrawal stroke so that the needle-thread-loop may be properly formed before the looper-point moves into loop-seizing position. In the present case, a pronounced dwell of the looper 44 is conveniently obtained by so arranging the looper supporting shaft bearing in the bracket 50 and the depending rock-arm 52 that when the needle 21

is at the extreme end of its work-penetrating stroke (see Fig. 3), the link 53 connecting the depending rock-arm 52 with the needle-bar extension 54 is disposed so that its longitudinal axis when extended forms with the longitudinal axis of the needle-bar 23 substantially a right angle. When arranged in this way the initial portion of the withdrawal stroke of the needle acts to pivot the link 53 about the lower end of the depending rock-arm 52 without imparting to the link 53 any appreciable endwise motion. In the absence of any endwise motion of the link 53, the rock-arm 52 does not turn the looper supporting shaft 49 in its bearing and therefore the looper 44 remains in a state of dwell. As the needle-bar 23 continues in its withdrawal stroke, and the period of dwell of the looper is terminated, the looper is oscillated about the axis of the looper supporting shaft 49, the looper slowly accelerating in speed until it reaches a maximum. The slow acceleration of the looper during the period in which it seizes and enters the needle-thread-loop is of importance in that during the seizure of the thread-loop the latter is not subjected to any abrupt strain, with the result that thread-breakage is reduced to a minimum and the setting of the previously formed stitch may be more readily accomplished.

As previously described the looper, after entering the thread-loop cast out by the needle, presents its own thread to a spreader which distends the looper-thread-loop for entrance by the needle prior to its penetration of the fabric. In the present disclosure, the spreader 58, bifurcated at its free end, is formed with a flattened shank 59 removably fastened by a screw 60 upon the upper end of a short inclined supporting shaft 61 journaled for oscillation only in spaced bearing lugs 62 and 63 formed integral with the machine-frame 1. While not essential, it will be observed in Fig. 3 that the longitudinal axis of the spreader-supporting shaft 61 lies in a vertical plane which intersects the vertical plane containing the axis of the needle-bar 23 at substantially a right angle. Clamped upon the supporting shaft 61 intermediate the bearing lugs 62 and 63 is a rearwardly and upwardly inclined rock-arm 64 having connected thereto at its upper end, through a ball-and-socket joint, the upper end of a pitman 65 actuated by an eccentric 66 fixed upon the main-shaft 8.

As will be observed in Figs. 1 and 3, the upper end-portion of the pitman 65 operates through a clearance opening 67 in the forward wall of the splash-lubrication compartment 1. It is required that the opening 67 be of a size substantially larger than the size of the pitman 65, since the latter in imparting oscillatory movements to the spreader-supporting shaft 61 has a lateral movement as well as an endwise movement. To prevent oil from being splashed out of the compartment 1 during the operation of the machine, the opening 67 at its inner end is substantially closed by a baffle-member 68, shown in Fig. 2. The baffle-member, which is adapted to be attached to the under surface of the horizontal partition 6 by a fastening-screw 69, Fig. 1, comprises a sheet-metal right-angle-plate 70 having in its horizontal limb an elongated slot 71 for the fastening screw 69 and having in its vertical limb a cut-out 72 forming two depending supporting plate-members 73 and 74. Secured, preferably by rivets 75 and washers 76, to the supporting plate-members 73 and 74 are two resilient sections 77 composed of felt, rubber, or the 75

like. Each of the resilient sections is provided with a relatively small clearance aperture 78 through which works the pitman 65. To facilitate assembly or renewal of the baffle-member 68, the resilient sections are vertically split, as at 79, whereby the baffle-member may be conveniently placed upon the pitman 65 for attachment to the horizontal partition 6.

From the foregoing, it will be understood that 10 I have provided a stitch-forming mechanism for a so-called cup-feed sewing machine including a needle 21 and two thread-manipulating devices 44 and 58, the needle being reciprocated endwise in a substantially horizontal plane and the two thread-manipulating devices being oscillated each in a single plane only for cooperation with the needle. Simple oscillatory movement of each of the two thread-manipulating devices is all that is required to effect stitch-formation 15 because of the angular arrangements of the supporting shafts 49 and 61, as best shown in Figs. 3 and 7.

In Fig. 8 the spreader has been replaced by a threaded secondary looper 80, thus converting 20 the two-thread machine into a three-thread machine. When fitted to sew with three threads, the thread T_p on the primary looper 44, instead of being distended for entrance by the needle 21, is seized by the secondary looper 80, thereby 25 enchaining the thread T_p on the primary looper 44 with the thread T_s on the secondary looper 80. After so enchaining the two threads, the secondary looper presents its thread T_s to the needle for entrance by the same prior to its 30 penetration of the fabric sections. By the mere substitution of a threaded looper for a spreader the machine disclosed may be fitted to make a three-thread overseam instead of a two-thread overseam.

40 As is common in overseaming machines of the type disclosed there is provided a stitch-finger overlying the feed-cups 4 and 5 at the stitching-point and about which the stitches are formed and set to minimize distortion of the marginal edges of the fabric sections being sewn. The 45 stitch-finger as disclosed comprises an attenuated substantially conical blade 81 terminating in an abruptly inclined looper-thread-positioning shoulder 82 having a crest 83 at the top of the shoulder 82 and a trough 84 at the junction of the blade 81 and the shoulder 82, and a horizontally projecting needle-thread-loop positioning fin 85 having a curved thread-engaging edge 85'. The shank 86 of the stitch-finger is 50 secured by two screws 87 upon a support 88 disposed within the upturned peripheral flange of the inner feed-cup 4 and sustained by two screws 89 to an angle-bracket 90 fastened to the standard-wall. The support 88 beneath the blade 81 of the stitch-finger is formed with a needle-clearance slot 91 through which the needle 21 reciprocates. The stitch-finger in its under surface, as shown in Figs. 5, 6 and 13 is formed with an inclined cut-out 92 which functions as 55 an edge-guide in maintaining the edges of the fabric sections a predetermined distance above the needle.

The function performed by the stitch-finger is illustrated clearly in Figs. 13 to 17, inclusive. 70 As described hereinbefore, at the beginning of the stitch-forming cycle the needle 21 penetrates the fabric sections F and at the initial portion of the needle-return or withdrawal stroke casts out a substantially vertical thread-loop T_n , as shown in Fig. 13. This thread-loop, if correctly

positioned, is entered by the point of the threaded looper 44 which enchains its thread T_p with the thread T_n carried by the needle. It has been found that occasionally the needle-thread-loop, instead of being formed vertically as shown in Fig. 13, is cast out and twisted into a more or less horizontal position to the right of the needle-blade. When the needle-thread-loop is in this abnormal position, the point of the looper 44 cannot enter said loop and a skipped stitch results. To eliminate this skipping of stitches, the stitch-finger has been formed with a horizontally projecting needle-thread-loop positioning fin 85 having a curved thread-engaging edge 85'. The purpose of this curved edge 85' is to provide a stationary abutment against which the upper limb of the needle-thread-loop T_n will ride during the withdrawal stroke of the needle 21. During the sewing operation, if the needle-thread-loop tends to lay over into a more or less horizontal position, the contact of the upper limb of the needle-thread-loop with the curved thread-engaging edge 85' of the fin 85 will right the needle-thread-loop into its normal vertical position so that it may be easily entered by the point of the looper 44. The provision of the needle-thread-loop positioning fin 85 assists to a great extent in minimizing the skipping of stitches during high speeds of operation of the machine.

In addition to the fin 85 for controlling the needle-thread-loop, the stitch-finger is fitted with a shoulder 82 for assisting in positioning the looper-thread-loop for entrance by the needle. As shown in Figs. 14 and 15, when the needle 21 reaches substantially the end of its withdrawal stroke, the spreader 58 engages one limb of the looper-thread T_p and lays said limb over the crest 83 of the shoulder 82. As the spreader 58 continues downwardly in its loop-distending stroke it draws the limb of the looper-thread T_p over the crest 83 and down the inclined shoulder 82 to the trough 84 at the base of the shoulder 82, see Figs. 16 and 17. As shown in Fig. 4, the crest 83 is at one side of the path of needle-reciprocation and the trough 84 is at the opposite side of the path of needle-reciprocation. This movement of the limb of the looper-thread-loop down the shoulder and into the trough 84 results in an opening up of the looper-thread-loop so that during the next work-penetrating stroke of the needle 21 it will unerringly enter the looper-thread-loop prior to its penetration of the fabric sections. It is essential that the trough 84 be spaced to one side of the line of needle-reciprocation a distance at least equal to the shortest stitch-length to which the machine can be adjusted for, as shown in Figs. 16 and 17, this forms a V-shaped thread-loop between the trough 84, spreader 58 and the eye in the looper 44. It will be understood that the wider the thread-loop is spread by the trough, the less likelihood exists that the point of the needle 21 will fail to enter the looper-thread-loop.

Figs. 9, 10, 11 and 12 disclose an uncurling guide with which the machine is fitted when seaming hosiery and the like. As shown in Fig. 9, the uncurling guide is located directly in front of the feed-cups and functions to uncurl and direct the edges of the fabric preparatory to stitching. The present uncurling guide forms the subject of my copending divisional application Serial No. 303,946, filed Nov. 13, 1939, which matured into U. S. Patent No. 2,256,672 on Sept. 23, 1941, and is a modification of the uncurling guide disclosed

in my U. S. Patent No. 2,256,881, issued Sept. 23, 1941, the following description having to do particularly with the latching device for holding the uncurling guide in operative or inoperative position.

The guide includes a central guiding plate 93 terminating at its upper end in a supporting head portion 94. Disposed on opposite sides of the guiding plate adjacent its lower end are uncurlers 95 yieldingly pressed by the usual spring 96 against the faces of the guiding plate. The mounting for the uncurling guide is identical with that shown and described in my pending application above mentioned.

Referring to Fig. 10, it will be seen that the supporting head portion 94 of the central guiding plate 93 is formed with a bearing aperture 97 through which projects a cylindrical boss 98 formed upon a stationary locking disk 99. The locking disk is rigidly fastened face to face to the vertical plate 100 by a bolt 101, with the head 94 of the central guiding plate 93 interposed between the vertical plate 100 and the locking disk 99. To permit the central guiding plate 93 to turn freely upon the boss 98, the width of said boss is slightly in excess of the thickness of the central guiding plate.

To positively hold the uncurling guide in set positions, the locking disk 99 is formed with two notches 102 and 103. Cooperating with these notches are two pivotal latches 104 and 105 biased toward each other by a coil-spring 106 connected by shouldered screws 107 and 108 to the free ends of the latches. The two latches are apertured as at 109 and 110 to receive a fulcrum-stud 111 threaded into an ear 112 formed on the head 94 of the central guiding plate 93. Latch 104 has secured to it by screws 107 and 113 a control-lever 114 having at its free end an offset finger-piece 115. Latch 105 has similarly secured to it by screws 108 and 116 a control-lever 117 having at its free end an offset finger-piece 118. The two control-levers 114 and 117 cross each other, the control-lever 117 being bent as at 119 to provide clearance for the control-lever 114, whereby independent movement of one control-lever will not interfere with the other control-lever.

Referring now to Fig. 9, it will be understood that the uncurling guide is shown in full lines in its normal operative position. In such position the latch 104 is disposed in the notch 102 in the locking disk 99, see Fig. 11, while the latch 105 rides on the periphery of the locking disk, the latch 104 being held in the notch 102 by the coil-spring 106. When it is desired to shift the uncurling guide out of operative position and into the position shown in dotted lines in Fig. 9, the control-lever 114 is moved in a counterclockwise direction and the initial movement of the control-lever 114, which movement is independent of the central guiding plate 93, raises the latch 104 out of the notch 102. When the latch is entirely clear of the notch, the control-lever 114, the control-lever 117, and the central guiding plate 93 move as a unit, turning the guide about the axis of the cylindrical-boss 98 on the locking disk 99 until the latch 105 registers with and enters the notch 103 in the locking disk. During this turning of the guide the latches 104 and 105 ride upon the periphery of the locking disk 99, the coil-spring 106 being sufficiently strong so that pressure on the control-lever 114 in a counterclockwise direction will not tend to lift the latch 104 off the periphery of the locking disk 99, but will

effect a substantially rigid connection between the control-lever 114 and the guide.

When it is desired to return the uncurling guide to operative position, such as shown in full lines in Fig. 9, the control-lever 117 is turned in a clockwise direction, thereby first moving the latch 105 out of the notch 103 and, secondly, turning the guide about the boss 98 until the latch 104 registers with and enters the notch 102 in the locking disk 98. The two control-levers 114 and 117 are designed for independent operation and when it is desired to move the guide into inoperative position control-lever 114 is operated, and when it is desired to return the guide to operative position control-lever 117 is operated.

From the above description, it will be apparent that an uncurling guide has been provided having means including two latches, each having its own control-lever for positively locking the guide in or out of operative position. In the embodiment chosen for illustration, the control-levers 114 and 117 are each removably secured to its respective latch by means of screws. Obviously the control-lever may be formed integral with the latches 104 and 105 without departing from the invention. In Fig. 9, it will be seen that the free ends of the control-levers, when the guide is in operative position, are preferably positioned in advance of the guide so that the operator may conveniently strike the control-lever 114 with an upward movement of the hand to shift the guide into inoperative or loading position, and strike the control-lever 117 with a downward movement of the hand to shift the guide back into operative position.

Having thus set forth the nature of the invention, what I claim herein is:

1. A sewing machine having, in combination, a frame, a main-shaft journaled in said frame, feeding mechanism, stitch-forming devices including a threaded needle and a supplemental looper adapted to seize thread-loops presented by said needle, a needle-carrier operating through a wall of said frame, means within said frame for operatively connecting said needle-carrier to said main-shaft, and means externally of said frame for connecting said looper to said needle-carrier for actuating said looper in timed relation with said needle.

2. A sewing machine having, in combination, a frame, a main-shaft journaled in said frame, feeding mechanism, stitch-forming devices including a threaded needle and a looper cooperating therewith, a reciprocatory needle-bar carrying said needle, means operatively connecting said needle-bar to said main-shaft, a looper-shaft supporting said looper, and means comprising a link and arm connecting said looper-shaft directly to said needle-bar for actuating said looper in timed relation with said needle.

3. A sewing machine having, in combination, a frame, a main-shaft journaled in said frame, feeding mechanism, stitch-forming devices including a threaded needle and a looper cooperating therewith, a reciprocatory needle-bar journaled in said frame and carrying said needle, means within said frame for operatively connecting said needle-bar to said main-shaft, a looper-shaft supporting said looper, and means externally of said frame for connecting said looper-shaft to said needle-bar for actuating said looper in timed relation with said needle.

4. A sewing machine having, in combination, a frame, a main-shaft journaled in said frame, feeding mechanism, stitch-forming devices in-

cluding a threaded needle and a looper cooperating therewith, a reciprocatory needle-bar journaled in said frame and carrying said needle, means within said frame for operatively connecting said needle-bar to said main-shaft, a looper-shaft supporting said looper and arranged so that its longitudinal axis cuts the vertical plane containing the longitudinal axis of said needle-bar at an angle, and means externally of said frame for connecting said looper-shaft to said needle-bar for actuating said looper in timed relation with said needle.

5. A sewing machine having, in combination, a frame, a main-shaft journaled in said frame, feeding mechanism, stitch-forming devices including a threaded needle and a looper cooperating therewith, a reciprocatory needle-bar carrying said needle, means for operatively connecting said needle-bar to said main-shaft, a looper-shaft supporting said looper, a rock-arm secured to said looper-shaft, and a link connecting said rock-arm to said needle-bar for oscillating said looper in timed relation with said needle.

6. A sewing machine having, in combination, a frame, a main-shaft journaled in said frame, feeding mechanism, stitch-forming devices including a threaded needle and two cooperating oscillatable elements at least one of which is threaded, a carrier for said needle, means for actuating said needle-carrier, shafts supporting said two oscillatable elements, means including a link and rock-arm for connecting one of said element-supporting shafts to said needle-carrier, and means connecting the other of said element-supporting shafts to said main-shaft.

7. A sewing machine having, in combination, a frame, a main-shaft journaled in said frame, feeding mechanism, stitching-forming devices including a threaded needle and two cooperating oscillatable elements at least one of which is threaded, a carrier for said needle operating through a wall of said frame, means for actuating said needle-carrier, shafts for supporting said two oscillatable elements, means externally of said frame for connecting one of said element-supporting shafts to said needle-carrier, and means including a connection penetrating said frame for connecting the other of said element-supporting shafts to said main-shaft.

8. A sewing machine having, in combination, a frame, feed-cups exteriorly of and supported by said frame for sustaining and feeding fabric sections, stitch-forming devices including a threaded needle and a cooperating looper, a reciprocatory needle-bar journaled horizontally in said frame, an actuating shaft mounted in said frame, means within said frame for connecting said needle-bar to said actuating shaft, a looper-carrier for supporting said looper, and means externally of the frame for operatively connecting said looper-carrier to said needle-bar.

9. A sewing machine having, in combination, a frame including a standard and an overhanging bracket, a main-shaft journaled in said frame, feed-cups exteriorly of and supported by the frame beneath said overhanging bracket for sustaining and feeding fabric sections, stitch-forming devices including a threaded needle and two cooperating oscillatable elements at least one of which carries a thread, a carrier for said needle, means within said frame for actuating said needle-carrier, shafts supporting said two oscillatable elements, means externally of said frame for connecting one of said element-supporting shafts to said needle-carrier, and means including a con-

nection penetrating said frame for connecting the other of said element-supporting shafts to said main-shaft.

10. A sewing machine having, in combination, a frame including a standard and an overhanging bracket, feed-cups exteriorly of and supported by said frame for sustaining and feeding fabric sections, stitch-forming devices including a needle and a cooperating looper, a reciprocatory bar carrying said needle and journaled horizontally in said frame, a looper-shaft for said looper sustained by said overhanging bracket, and means for operatively connecting said looper-shaft to said needle-bar.

11. In a sewing machine, the combination with a frame including a standard and an overhanging bracket, and feed-cups exteriorly of and supported by said frame for sustaining and feeding fabric sections, of stitch-forming devices including a needle and two cooperating oscillatable elements, a reciprocatory bar carrying said elements, a shaft supporting one of said oscillatable elements, a rock-arm secured to said shaft, a link operatively connecting said rock-arm to said reciprocatory needle-bar, a second shaft supporting the other of said oscillatable elements, a rock-arm secured to said second shaft, and means including a pitman for actuating the rock-arm secured to said second shaft.

12. In a sewing machine, the combination with a frame including a standard and an overhanging bracket, a main-shaft, and feed-cups exteriorly of and supported by said frame for sustaining and feeding fabric sections, of stitch-forming devices including a needle, a looper and a spreader, a reciprocatory bar carrying said needle, an oscillatory shaft supporting said looper, means connecting said looper-oscillatory shaft to said needle-bar, a second oscillatory shaft supporting said spreader, and means for operatively connecting said spreader-oscillatory shaft to said main-shaft.

13. A sewing machine having, in combination, a frame, a main-shaft journaled in said frame, feeding mechanism for advancing fabric sections through the machine, stitch-forming devices including a threaded needle and a cooperating threaded looper for producing overseaming stitches, and a stitch-finger having means for correctly positioning the needle-thread-loop for entrance by the looper and means for properly spreading the looper-thread-loop for entrance by the needle on its succeeding work-penetrating stroke.

14. A sewing machine having, in combination, a frame, a main-shaft journaled in said frame, feeding mechanism, stitch-forming devices including a threaded needle and a cooperating threaded looper for producing overseaming stitches, and a stitch-finger having a needle-thread-loop positioning fin and a looper-thread-loop positioning shoulder.

15. A stitch-finger for use on an overseaming sewing machine, comprising a shank, a blade about which the stitches are formed and set, a laterally extending fin for controlling and positioning the needle-thread-loop for entrance by the needle, and an inclined shoulder terminating at the base of said blade for spreading the looper-thread-loop for entrance by the needle on its succeeding work-penetrating stroke.

16. A sewing machine having, in combination, a frame provided with a depending bracket located outside of said frame, feed-cups exteriorly of said frame for sustaining and feeding fabric

sections, stitch-forming devices including a needle and a pair of thread-handling implements complementary to said needle in the formation of stitches, a reciprocatory bar carrying said needle and journaled in said frame, a shaft carrying one of said thread-handling implements and disposed in said depending bracket so that its longitudinal axis is arranged at an acute angle to the vertical plane containing the longitudinal axis of said needle-carrying bar, means for actuating said shaft in timed relation with said needle, an inclined shaft carrying the other of said thread-handling implements, and means for actuating said inclined shaft.

15. 17. A sewing machine having, in combination, a frame, feed-cups exteriorly of said frame for sustaining and feeding fabric sections, stitch-forming devices including a needle and a pair of thread-handling implements complementary to said needle in the formation of stitches, a reciprocatory bar carrying said needle and journaled in said frame, a shaft carrying one of said thread-handling implements and disposed so that its longitudinal axis is arranged in a substantially horizontal plane and at an acute angle to the vertical plane containing the longitudinal axis of said needle-carrying bar, means for operatively connecting said shaft to said needle-carrying bar, an inclined shaft carrying the other of said thread-handling implements, and means for actuating said inclined shaft.

18. A sewing machine having, in combination, a frame including a standard and an overhanging bracket, feed-cups exteriorly of said frame and beneath said overhanging bracket for sustaining and feeding fabric sections, stitch-forming devices including a needle, looper and spreader, a reciprocatory bar carrying said needle, a shaft carrying said looper and disposed so the vertical plane containing its longitudinal axis intersects the vertical plane containing the longitudinal axis of the needle-carrying bar at an angle, means for imparting operative movements to said shaft, an inclined shaft carrying said spreader and disposed so that the vertical plane containing its longitudinal axis intersects the vertical plane containing the longitudinal axis of the needle-carrying bar at substantially a right angle, and means for imparting operative movements to said spreader-carrying shaft.

19. The combination as called for in claim 18, in which the shaft carrying said looper is connected by mechanism to be operated directly by said reciprocatory needle-carrying bar.

20. An improved stitch-forming mechanism for cup-feed sewing machines having a frame including a standard and a main-shaft journaled in said standard, comprising, a needle and a pair of thread-handling implements complementary to said needle in the formation of stitches, a carrier for said needle operatively connected to said main-shaft within said standard, a carrier for one of said thread-handling implements disposed exteriorly of said standard and connected to be operated by the carrier for said needle, a carrier for the other of said thread-handling implements disposed also exteriorly of said standard, and means extending through a wall defining said standard and operatively connecting said last named carrier to said main-shaft for actuation thereby.

21. An improved stitch-forming mechanism for cup-feed sewing machines having a frame including a standard and a main-shaft journaled in said standard, comprising, a needle and a pair

of thread-handling implements complementary to said needle in the formation of stitches, a needle-bar journaled for endwise reciprocation in a wall defining said standard, means within said standard operatively connecting said needle-bar to said main-shaft, a shaft exteriorly of said standard and adapted to support one of said thread-handling implements, means connecting said shaft to said needle-bar for actuation thereby, a second shaft also exteriorly of said standard and adapted to support the other of said thread-handling implements, and means including a connection extending through the wall defining said standard for operatively connecting said second shaft to said main-shaft for actuation thereby.

22. An improved stitch-forming mechanism for cup-feed sewing machines having a frame formed with a closed lubrication compartment and a main-shaft extending through said lubrication compartment, comprising, a needle and a pair of thread-handling implements complementary to said needle in the formation of stitches, a needle-bar reciprocably journaled in an oil-tight bearing in a wall defining said lubrication compartment, means within said lubrication compartment for operatively connecting said needle-bar to said main-shaft, a shaft exteriorly of said frame and adapted to support one of said thread-handling implements, means connecting said shaft to said needle-bar for actuation thereby, a second shaft also exteriorly of said frame and adapted to support the other of said thread-handling implements, means including a connection having endwise as well as lateral movements extending through the wall defining said lubrication compartment for operatively connecting said second shaft to said main-shaft for actuation thereby, and oil-sealing means preventing the escape of oil at the point where said connection extends through the wall of the lubrication compartment.

23. The improvement as called for in claim 22, in which the oil-sealing means includes a plurality of spaced resilient sections apertured to provide clearance for said operating connection.

24. A stitch-forming mechanism for cup-feed sewing machines having a frame and a main-shaft journaled in said frame, comprising, a reciprocatory needle and mechanism complementary to said needle including a looper having a pronounced dwell in its operative movements at the beginning of the retracting movement of said needle, a needle-bar operatively connected to said main-shaft, a looper-carrier, and operating connections between said needle-bar and looper-carrier for actuating said looper.

25. A stitch-forming mechanism for cup-feed sewing machines having a frame and a main-shaft journaled in said frame, comprising, a reciprocatory needle and mechanism complementary to said needle including a looper having a retracted position relative to said needle, a needle-bar journaled for endwise reciprocation in said frame and operatively connected to said main-

5 shaft, a looper-carrier supporting said looper, and means including a link for operatively connecting said looper-carrier to said needle-bar, the longitudinal axis of said link forming substantially a right angle with the longitudinal axis of said needle-bar when the looper is in its retracted position.

10 26. A stitch-forming mechanism for cup-feed sewing machines having a frame and a main-shaft journaled in said frame, comprising, a reciprocatory needle and mechanism complementary to said needle including a looper having a pronounced dwell in its operative movements at the beginning of the withdrawal stroke of said needle, 15 a needle-bar journaled in said frame and operatively connected to said main-shaft, a looper-shaft supporting said looper, a rock-arm fixed to said looper-shaft, and a link connected at one end to said rock-arm and at its other end 20 to said needle-bar.

25 27. A stitch-forming mechanism for cup-feed sewing machines having a frame and a main-shaft journaled in said frame, comprising, a threaded needle carried on the end of a reciprocatory needle-bar, a looper cooperating with said needle and having a pronounced dwell in its operative movements at the beginning of the withdrawal stroke of said needle, a looper-shaft supporting said looper and confined to movement 30 of oscillation, means operatively connecting said looper-shaft to said needle-bar, a thread-handling implement complementary to said looper and needle, a shaft supporting said thread-handling implement, and means for actuating said shaft.

35 28. A stitch-finger for use on an overseaming sewing machine having stitch-forming devices including a threaded reciprocatory needle and a complementary threaded looper, comprising, a shank, a blade about which the stitches are formed and set, and an inclined shoulder intermediate said shank and blade adapted for spreading the looper-thread-loop for entrance by the needle, said shoulder having a crest at one side of the path of needle-reciprocation and a trough at the other side of the path of needle-reciprocation.

40 29. A stitch-forming mechanism for cup-feed sewing machines having a frame provided with a bracket and a main-shaft journaled in said frame, comprising, a threaded needle and a pair of thread-handling implements complementary to said needle in the formation of stitches, a reciprocatory bar carrying said needle and journaled in said frame, a substantially horizontal shaft carrying one of said thread-handling implements and supported by said bracket exteriorly 45 of said frame so that its longitudinal axis lies in a vertical plane relatively convergent with the vertical plane containing the axis of said needle-carrying bar, means for actuating said shaft in timed relation with said needle, a carrier for the other of said thread-handling implements, and means for actuating said carrier.

HANS HACKLANDER.
